INVENTOR,

Margaret Booth

UNITED STATES PATENT OFFICE

MARGARET BOOTH, OF NEW YORK, N. Y.

FOOT RAIL

Application filed March 3, 1932. Serial No. 596,458.

This invention relates to foot-rails and more particularly to the folding type, appropriate for cabinet bars forming the subject matter of my Patent No. 1,862,654, of June 14, 1932, of which this application is a continuation in part, and also other forms of refreshment bars, or automobiles, and has for its object to provide a rail mounted on movable supports and therefore capable of being easily extended or retracted, and when in the latter position with the said supports concealed within the structure with which the foot-rail is associated. Another object is to provide means by which the fixture as a whole may be supported by the said structure independent of the floor beneath such structure when in an extended position, and a further object is to provide a device in which the rail when in a retracted position will closely embrace the contiguous surface of the wall of the said structure and thereby simulate a contour associated with said wall, with the supporting brackets for the rail operating within slots in said wall in such a manner as to close same and form a continuity of the outer surface of said wall.

It will be understood that the outer surface of the aforesaid brackets may be finished to correspond to the finish of the wall, such as a similar color or a harmonizing one, or it may be covered with leather, cloth or other material, if the surface of the associated structure be so covered. It may also be desirable to form this portion of the brackets to likewise represent an ornamental contour similar in character to that of the rail member of the device thereby producing the effect of a panel when the foot-rail is retracted and with or without a fourth complementary side which would be permanently carried by the wall. The brackets would then protrude slightly from the slots through which they operate.

In any event the foot-rail will be capable of being folded back into a compact position when it is desired to discontinue its use as a foot rest and prevent accidental stumbling against it, and with the supporting elements housed within the associated structure for concealment therein sufficiently, and in the manner set forth, to disguise the real character of the fixture. Further objects of the invention are hereinafter set forth in the following specification and drawing forming a

part thereof in which I have illustrated a preferred embodiment of my invention.

Referring to such drawing,

Fig. 1 is a front elevation of my improved foot-rail together with the supporting structure which may be associated therewith, and with the parts in an extended position and the central portion broken out.

Fig. 2 is a vertical section of same on a plane substantially through the center of Fig. 1.

Fig. 3 is an elevation similar to Fig. 1 but with the foot-rail in a retracted position.

Fig. 4 is a section similar to Fig. 2 but with the foot-rail in a retracted position.

Fig. 5 is a horizontal section on the line 5—5 of Fig. 2.

Fig. 6 is a plan view on a reduced scale showing the foot-rail applied to a bar or counter and,

Fig. 7 is a sectional view of a modified form of the invention.

Referring to Figures 1 to 5 the foot-rail is shown applied to an example of supporting structure such as having a front wall 1 and side walls 2 forming a compartment within which certain parts of the device are adapted to extend, and consists of brackets in the form of bell-crank levers 3 which are pivotally mounted at 4 on plates 5 which in turn are secured to the inner walls of the sides 2 of the structure 1. The levers 3 are provided with forward arms 6 and rearward arms 7, and are adapted to swing through slots 8 in the wall 1 adjacent the sides 2. The forward arms 6 of levers 3 are secured at their outer ends to a rail member 9, as by screws or bolts 9', so that the rear surface of the rail member will contact with the forward surface of the said arms and with the rail member forwardly of said arms and extending slightly beyond and above the ends thereof as shown in Fig. 2. A web 6' between arm 6 and arm 7 adds rigidity, and a web 7' extends rearwardly from arm 7 and carries a boss 10 within which is secured a pin 11 projecting laterally therefrom toward the side 2 and which is adapted to engage an arcuate slot 12 formed in plates 5 and centering about the pivot 4. Arm 6 forward of the web portion 6' is substantially equal in width to the width of the slot 8, and arm 7 forward of the web portion 7' is likewise wide enough to equal the width of said slot.

When the foot-rail is swung outwardly into the extended position shown in Fig. 2 the

aforesaid wide portion of arm 7 will occupy the slot 8 and the outer surface of the arm will then be substantially flush with the outer surface of the front wall 1 of the associated structure, thus closing the otherwise unsightly open slot and providing a continuity of the wall surface as set forth.

Similar results are attained when the foot-rail is retracted as in Fig. 4, the arm 6 then functioning to close slot 8 for the same purpose. The arcuate slot 12 in each of the plates 5 is of suitable length to act as a stop for the pin 11 when the latter reaches either end thereof, so that the rail member 9 will be sustained in an extended position and at a desired height above the floor beneath the supporting structure, or in close proximity to the outer surface of the wall 1 when in a retracted position and without marring the finish thereof.

I have shown the rail member 9 of a suitable configuration to conform to the arches of the feet when contacting therewith while extended, and also of further configuration so that when retracted it will simulate, for example, a moulding or the like constituting a part of the associated supporting structure.

Arm 7 which includes the web 7' and boss 10, is purposely made more bulky than arm 6 to increase its weight relatively and in this manner operate to slightly overbalance the latter arm together with the rail member so that the fixture when once retracted will remain in such position under forces of gravity acting thereon as will be apparent.

In the modification shown in Fig. 7 supporting bars 15 are substituted for the levers 3, which are adapted to slide in guide members 16 secured to the sides 2 of the supporting structure. A rail member 17 is secured to the outer ends of the bars 15 and is of a suitable configuration to provide a foot rest when the device is extended as shown, or when in a retracted position with rail 17 contiguous with wall 1, to simulate a contour associated with the same, as in the preferred embodiment. Suitable stops 18 may be provided as shown to limit the extent of the outward movement of the rail member.

The fixture may be assembled and mounted on the supporting structure because the rail member thereof is detachable. During such assembly the bell-crank levers 3 are first slipped over the pivots 4 projecting from plates 5, or they may be permanently pivoted thereto, and the levers are then passed through the slots 8 from within the structure and toward the outside thereof. The plates 5 may then be fastened in place on the side walls a hole 7" in web 7' of arm 7 being provided for the insertion of one of the bolts or screws used for this purpose which would otherwise be covered by said web portion. The rail member may then be secured in its proper position on arms 6 by the means indi-

cated at 9', or in any suitable manner to provide sufficient rigidity for the purpose intended.

In applying the device to an automobile as a foot rest for the occupants of the rear seats of such vehicles, the slots 8 will be cut through the rear wall of the front seating structure, and the levers 3 will extend within such structure and beneath the front seat and at the ends thereof. The plates 5 may be modified dimensionally if necessary to cooperate with that part of the automobile body frame to which they might be secured, and the apparatus may be similarly extended as described, or retracted just as in Fig. 4, with the rail member close to or against the said rear wall of the front seat and with the levers or brackets 3 completely withdrawn from the rear seat compartment so that they cannot then interfere with anything it might be desirable to transport therein such as hand baggage etc., the full capacity of such compartment being then available for such purpose.

The foregoing description is merely illustrative and not intended as limiting the invention thereto.

I claim:

1. The combination with a supporting structure having a wall with slots therein, of a folding foot-rail comprising a rail member, and brackets secured to and bridged by said rail member, and pivotally secured to said structure so as to be capable of swinging through said slots, said brackets being adapted to substantially disappear within said structure when said foot-rail is in a retracted position with respect to said structure, and essentially close said slots with the outer surface of said brackets thereupon forming a complementary part of the contour of the adjacent outer surface of said wall.

2. The combination with a supporting structure having a wall with slots therein, of a folding foot-rail comprising a rail member, and brackets secured to and bridged by said rail member, and pivotally secured to said structure so as to be capable of swinging through said slots, said brackets being adapted to substantially disappear within said structure when said foot-rail is in a retracted position with respect to said structure, and essentially close said slots with the outer surface of said brackets thereupon forming a complementary part of the contour of the adjacent outer surface of said wall, and with said rail member then in close proximity to said outer wall surface thereby simulating a contour associated with said wall.

3. The combination with a supporting structure having a wall with slots therein, of a folding foot-rail comprising a rail member, and brackets secured to and bridged by said rail member, and pivotally secured to said structure so as to be capable of swinging

- through said slots, said brackets being adapted to substantially disappear within said structure when said foot-rail is in a retracted position with respect to said structure, and 5 essentially close said slots with the outer surface of the portion of said brackets occupying said slots substantially flush with the adjacent outer surface of said wall, the configuration of said brackets being such that 10 another portion thereof will close said slots in the aforesaid manner when said rail member is in an extended position.
4. The combination with a supporting structure having a wall with slots therein, of 15 a folding foot-rail comprising a rail member, and brackets secured to and bridged by said rail member, and pivotally secured to said structure so as to be capable of swinging through said slots, said brackets being 20 adapted to substantially disappear within said structure when said foot-rail is in a retracted position with respect to said structure, and essentially close said slots with the outer surface of the portion of said brackets 25 occupying said slots substantially flush with the adjacent outer surface of said wall, the configuration of said brackets being such that another portion thereof will close said slots in the aforesaid manner when said rail 30 member is in an extended position, and the position of said rail member when retracted being then in close proximity to said outer wall surface thereby simulating a contour associated with said wall.
- 35 5. The combination with a supporting structure having a wall with openings therein, of an extensible foot-rail comprising a rail member, and supports secured thereto and adapted to be moved through said open- 40 ings to extend said rail member or retract same with respect to said wall, said rail member when retracted being then substantially in contact with the contiguous surface of said wall to simulate an ornamental con- 45 tour associated therewith, and said supports constituting the only supporting members carried by said rail.
6. The combination with a supporting structure having a wall with slots therein, 50 of a folding foot-rail comprising a rail member, and bell-crank levers pivotally secured to brackets carried by said structure so as to be capable of swinging through said slots, one arm of each of said levers extending for- 55 wardly out of said slots when said foot-rail is in an extended position, and being secured to said rail member, and the other arm thereof extending rearwardly within said structure, and means operatively asso- 60 ciated with said latter arm and carried by said brackets for limiting the movement of said lever to thereby support said rail member in such extended position.
7. The combination with a supporting structure having a wall with slots therein, of a folding foot-rail comprising a rail member, and bell-crank levers pivotally secured to brackets carried by said structure so as to be capable of swinging through said slots, one arm of each of said levers extending forwardly out of said slots when said foot-rail is in an extended position, and being secured to said rail member, and the other arm thereof extending rearwardly within said structure, and means operatively associated with said latter arm and carried by said brackets for limiting the movement of said lever to thereby support said rail member in such extended position, 70 75 80 85 90 95 100 105 110 115 120 125
8. The combination with a supporting structure having a wall with slots therein, of a folding foot-rail comprising a rail member, and bell-crank levers pivotally secured to brackets carried by said structure so as to be capable of swinging through said slots, one arm of each of said levers extending forwardly out of said slots when said foot-rail is in an extended position, and being secured to said rail member, and the other arm thereof extending rearwardly within said structure, and means operatively associated with said latter arm and carried by said brackets for limiting the movement of said lever to thereby support said rail member in such extended position, the former arm being adapted to occupy and substantially close said slots when said foot-rail is in a retracted position.
9. The combination with a supporting structure having a wall with slots therein, of a folding foot-rail comprising a rail member, and bell-crank levers pivotally secured to brackets carried by said structure so as to be capable of swinging through said slots, one arm of each of said levers extending forwardly out of said slots when said foot-rail is in an extended position, and being secured to said rail member, and the other arm thereof extending rearwardly within said structure, and means operatively associated with said latter arm and carried by said brackets for limiting the movement of said lever to thereby support said rail member in such extended position, each of said arms being adapted to occupy and substantially close said slots when in relative positions corresponding respectively to the extended or retracted positions of said foot-rail, and with the respective outer surface of each substantially flush with the adjacent outer surface of said wall.

MARGARET BOOTH.
